UNITED STATES PATENT OFFICE.

SAMUEL ZWICK, OF SOUTH MANCHESTER, CONNECTICUT.

WRENCH.

1,114,423.

Specification of Letters Patent. Patented Oct. 20, 1914.

Application filed June 12, 1914. Serial No. 844,766.

To all whom it may concern:

Be it known that I, SAMUEL ZWICK, a subject of the King of Austria-Hungary, residing at South Manchester, in the county of 5 Hartford and State of Connecticut, have invented certain new and useful Improvements in Wrenches, of which the following is a specification.

This invention relates to wrenches, and 10 more particularly to a wrench having a stationary jaw and a slidable jaw adjustably mounted relative to the stationary jaw.

The object of my invention is to provide a wrench of the above described type which 15 shall be simple in construction, cheap to manufacture and effective in operation.

Another object of my invention is to provide an effective locking means for the slid- 20 able jaw of a wrench of the above character.

Another object of my invention is to provide a means that automatically disengages the locking means on the slidable jaw to allow of the movement of the same.

With the above and other objects in view 25 my invention resides in the construction, combination and arrangement of the parts as set forth in the following specification and illustrated in the accompanying drawings, in which:

Figure 1 is a side elevation of a wrench in which the preferred form of my invention is embodied. Fig. 2 is a like view having the slidable jaw in section so as to show the interior of the same. Fig. 3 is a transverse 35 sectional view taken on the line 3-3 of Fig. 2.

Similar reference characters indicate similar parts throughout the various views of the drawings.

Referring more particularly to the drawings in which the preferred embodiment of my invention is shown, the numeral 1 indicates the handle of a wrench and 2 indicates the shank of the same having one edge 45 thereof provided with a plurality of teeth 3. 4 indicates the stationary jaw integrally formed with the shank 2 of the wrench.

In the preferred form of my invention I provide a slidable jaw 5, which in the present 50 instance comprising a U-shaped portion 6 which is adapted to embrace the shank 2 of the wrench, the sides of the U-shaped portion 6 are adapted to engage in the cut out portion 8 of the jaw 5 and be secured thereto by means of the screws 9. While I have 55 shown these parts as formed detachably it

will be readily understood that the same may be cast in one solid piece having a central opening therethrough to receive the shank 2. The portion of the jaw 5 adjacent the teeth 3 of the shank 2 is provided with a ridge 10, having complementary teeth 11 for engaging with the teeth 3 formed thereon. Springs 12 are provided for disengaging the aforesaid teeth 11 and 3, each of the springs 12 having an end thereof secured to the jaw 5 on the ledge or flange 13 formed on the aforesaid jaw 5, the opposite ends of the springs 12 being adapted to engage the under surface of the shank 2 and bent to force the 60 same away from the jaw 5. To lock the said teeth 11 and 3, I provide a cam member 14, pivoted in an opening 15, on a pin 16, in the U-shaped portion 6, the cam portion 17 thereof being adapted to engage the upper 65 edge 18 of the shank 2, and when the cam is in position as shown in Fig. 2, the teeth 11 and 3 will be engaged, thereby preventing longitudinal movement of the jaw 5 relative to the shank 2. The handle portion 19 of 70 the cam member 14 is adapted to seat in a cut-out portion 20 of the said U-shaped member 6 whereby to prevent accidental movement of the cam member 14. The stationary jaw 4 may be used as a hammer, 75 and the end of the handle 1 is provided with a tapered portion 21 to serve as a screw driver.

From the above, it will be seen that I have provided a simple and effective means for 80 locking the slidable jaw of a wrench at any position along the length of the shank of said wrench. To operate my improved locking means, when it is desired to move the jaw 5 along the shank 2, the cam member is 85 raised. The springs 12 will now force the teeth 11 on the jaw 5 out of engagement with the teeth 3 on the shank 2, thereby allowing the said jaw 5 to be moved longitudinally on the shank 2, adjusted to any position. 90 When the desired point is reached, where it is wished to lock the jaw 5, the cam member 14 is again forced down into the position shown in Fig. 2 which will cause the teeth 11 and 3 to engage and prevent movement of the jaw 5. A space 6' is provided between the U-shaped member 6 and the upper face 95 100 105 110 115 120 125 130 135 140 145 150 155 160 165 170 175 180 185 190 195 198 200 205 210 215 220 225 230 235 240 245 understood by those versed in the art that I may make such minor changes in the details of construction as will not depart from the spirit and scope of the appended claims.

5. What I desire to secure by Letters Patent is:

1. A wrench, including a shank having a rigid jaw on one end thereof, an inner toothed jaw slidably mounted on said shank, 10 teeth on said shank adapted to engage the teeth on the jaw, a cam member for facilitating the engagement of said teeth, and spring members supported on said slidable jaw in spring pressed relation with one of 15 the edges of the said shank on each side of the toothed portion thereof, whereby to insure an even distribution of the pressure of the spring.
2. A wrench, including a shank having a rigid jaw on one end thereof, an inner toothed jaw slidably mounted on said shank, 20 teeth on said shank adapted to engage the teeth on the jaw, a cam member pivotally mounted in said inner jaw and adapted to 25 contact with one of the edges of the shank for causing engagement with the aforesaid

teeth, springs on said inner jaw, said springs embracing the teeth of said shank and inner jaw, and the ends of said springs being pressed against one of the edges of the 30 shank, whereby to force the said shank out of engagement with the teeth on the inner jaw when the cam member is released.

3. A wrench, including a shank having a rigid jaw on one end thereof, an inner jaw 35 slidable on said shank, teeth on one edge of said shank adapted to engage with teeth on the inner jaw, means comprising flat spring elements carried by the movable jaw, and disposed on each side of the toothed portion 40 of the shank, said flat spring elements having their free ends oppositely disposed on the movable jaw to insure a distribution of the pressure, and a cam member on said 45 inner jaw for facilitating the engagement of the teeth.

In testimony whereof I affix my signature in presence of two witnesses.

SAMUEL ZWICK.

Witnesses:

AUSTIN H. KNIVER,
WILLIAM S. HYDE.
